UNITED STATES PATENT OFFICE.

BARTHOLOMEW GOMMENGINGER, OF ROCHESTER, NEW YORK.

IMPROVEMENT IN DOMES FOR HOT-AIR FURNACES.

Specification forming part of Letters Patent No. 124,807, dated March 19, 1872.

Specification describing a certain Improvement in Radiating-Domes for Hot-Air Furnaces, invented by BARTHOLOMEW GOMMENGINGER, of the city of Rochester, in the county of Monroe and State of New York.

Nature of the Invention.

This invention consists in combining with the dome of a hot-air furnace a partition-ring provided with covers on each side, which cover the openings from the combustion-pipes, whereby a direct or an indirect draught may be secured at pleasure; also, in the form and construction of the base of the dome, as hereinafter described.

General Description.

In the drawing, Figure 1 is a central vertical section of the dome; Fig. 2, a longitudinal section in line $x\ x$, Fig. 1; Fig. 3, a perspective view of a portion of the ring; Fig. 4, a view of one of the draught-inlets; Fig. 5, section of the base of the dome.

A represents the dome, which may be made to surmount the fire-pot and base of any ordinary hot-air furnace. B B are the combustion-pipes leading from the fire-chamber to the dome; and C is the closed central cone or chamber, which holds a portion of the heat and products of combustion, and simply serves as a radiator, the same being in common use. The dome consists simply of an annular hollow chamber, being covered at the top and bottom by the plates D D. The hollow space of this dome is divided into two compartments by a vertical annular partition or division-plate, E, which is in the form of a ring, open at both ends, and extends from top to bottom, as shown. This partition-ring is loose, so that it may be turned around to any position, and it is operated by a socket-stem, a, which projects through the dome, or by any other desired means. The inlet-openings b b from the combustion-pipes open centrally against the bottom of the partition-ring, so as to discharge equally into either of the compartments separated by the ring. The base D, in which these inlets are located, is made convex upon the inner side, as shown at c c, the object being to allow the ashes to slide off on either side, away from the bottom of the partition-ring, and thus prevent clogging. A flat space, however, is left under the edge of the ring, so that it will

keep in place and work easily. The plate, directly under the edge of the ring, is also perforated at intervals by small holes d d, Fig. 5, to allow the escape of such ashes as do gather under the ring from long standing. These several features of the convex plate and the perforations form one feature of my invention.

The bottom of the partition-ring is formed at its lower edge, outside and inside, with half-circular covers or caps f f, of size and shape to correspond with the half-circular inlet-openings b b of the combustion-pipes, which they are made to cover. They also stand in convex or arching form, to fit the arch of the base-plate D. These covers, outside and inside, are arranged to alternate or "break joints," being so located that when one set covers the openings on one side the other set uncovers the openings on the other side, and vice versa. Thus the openings on one side or the other are always open when the other set is closed. The object of this is to give either a direct or an indirect draught, as may be desired. When an indirect draught is to be produced, the holes in the outer compartment are covered, as shown in the drawing; and in that case the draught which enters the inner compartment passes through the part g in the partition-ring into the outer one, and finally escapes into the smoke-pipe h.

By the use of this partition-ring damper the furnace is self-cleaning at all times, as the ashes that deposit are swept off by the turning action. Thus the furnace is kept from filling up, and it cannot leak gas or smoke.

I am aware that flat-ring dampers have been employed to cover the openings in the same kind of drum, but these are objectionable, inasmuch as they lie flat and soon become obstructed by ashes. Separate rings have also to be used for the several compartments. Such an arrangement is also complicated and expensive. I make the central partition itself serve as the damper to cover and uncover the holes. The whole being in one piece instead of three, it is much simpler and cheaper, therefore. Being upright, it cannot clog, especially when the base D is made of the convex form shown, and the covers f f are made separated and detached.

My improvement greatly simplifies the construction of the furnace.

A furnace constructed with this dome can

be set in sheet-iron casings or in brick-work, as desired.

Claim.

What I claim, and desire to secure by Letters Patent, is—

1. In the radiating-drum of a hot-air furnace, I claim the ring E, provided with the covers *ff*, which alternate in position, said ring serving the double purpose of a partition and a damper, as herein described.

2. I claim constructing the base D of the drum-space of convex or arched shape, when

combined with the ring E and covers *ff*, in the manner and for the purpose specified.

3. I claim the ash-holes *d* in the plate D, combined with the ring E, in the manner and for the purpose specified.

In witness whereof I have hereunto signed my name in the presence of two subscribing witnesses.

B. GOMMENGINGER.
